12 Claims

ABSTRACT OF THE DISCLOSURE

Disclosed are combinations of an analgesic with p-chloroamphetamine and other amphetamines containing at least one substituent on the phenyl ring, and non-toxic acid addition salts thereof. When such combinations are administered, tolerance, physical dependence and addiction are not induced.

This invention relates to analgesics. More particularly, this invention is concerned with a method of producing a potent analgesic effect without addiction and novel compositions useful in such treatment.

Potent synthetic analgesics such as meperidine, methadone, anileridine, alphaprodine, piminodine, phenampromide, and diamppromide are known to induce physical dependence, or addiction liability, and tolerance. This limits their usefulness even though they are relatively inexpensive.

It has now been found according to the present invention that a potent analgesic effect can be induced in an animal, and particularly a human, without concomitant production of tolerance, physical dependence and addiction by the simultaneous or concomitant administration of a substituted amphetamine compound or its non-toxic acid addition salts, with a synthetic analgesic such as meperidine, methadone, codeine, anileridine, alphaprodine, piminodine, phenampromide, diamppromide, or pentazocine.

By "amphetamine compound" is meant a compound having a substituent on the phenyl ring of the amphetamine structure of the general formula

wherein R is hydrogen or a lower alkyl, particularly methyl or ethyl and R₁ is a halo group and particularly chloro or bromo, the nitro group and the trifluoromethyl group, and nontoxic physiologically acceptable acid addition salts thereof such as the hydrochloride, hydrobromide, sulfate, phosphate, fumarate, maleate, citrate and cyclohexanesulfonate salts. Specific amphetamines which can be used are p-chloro-amphetamine, p - chloro-N-methylamphetamine, m - trifluoromethylamphetamine, m - trifluoromethyl - N-methylamphetamine, p - trifluoromethyl-N-ethylamphetamine, p-nitroamphetamine and p-nitro-N-methylamphetamine.

The substituted amphetamine compound is capable of abolishing or markedly reducing the physical dependence and tolerance properties of the analgesic without significantly interfering with its analgesic action. Thus, the range of therapeutic utility and safety of the potent but addicting synthetic analgesics can be greatly increased by the simultaneous or concomitant administration of the substituted amphetamine compound and its non-toxic acid addition salts.

The amount of substituted amphetamine compound, in the form of its base or a non-toxic acid addition salt, which

can be administered to protect against inducing physical dependence and tolerance by an analgesic can vary over a broad range. However, enough should be administered to obtain the desired result while avoiding the administration of more than needed. Generally, from about 10 to 350 mg. of a substituted amphetamine compound and its non-toxic acid addition salts can be administered simultaneously or concomitantly with the administration of an effective dosage of an analgesic. The dosage of analgesic administered can vary, since the potency of the analgesics varies considerably between drugs. However, the amount of analgesic administered will generally be from about 2 to 300 mg.

Although the analgesic and substituted amphetamine compound and its non-toxic acid addition salts can be administered separately, either simultaneously or concomitantly with each other, it is much more suitable to administer them in unit dosage pharmaceutical compositions which contain an amount of each at least adequate when administered one or more dosages at a time to obtain an effective action in a human. There are, therefore, provided by this invention novel unit dosage pharmaceutical compositions which contain an effective amount of the analgesic, usually from about 2 to 300 mg. of such drug, and an effective amount of a substituted amphetamine compound in the form of its non-toxic acid addition salts, usually from about 10 to 350 mg. of such compound, which can be admixed, if advisable, with a pharmaceutical carrier to facilitate forming tablets, capsules, lozenges and liquid formulations. The compositions should generally contain about 0.5 to 75% by weight of the active ingredients.

Pharmaceutical carriers which are liquid or solid may be used. The preferred liquid carrier is water. Flavoring materials may be included in the solutions as desired.

Solid pharmaceutical carriers such as starch, sugar, talc and the like may be used to form powders. The powders may be used as such for direct administration to a patient or, instead, the powders may be added to suitable foods or liquids, including water, to facilitate administration.

The powders may also be used to make tablets, or to fill gelatin capsules. Suitable lubricants like magnesium stearate, binders such as gelatin, and disintegrating agents like sodium carbonate in combination with citric acid may be used to form the tablets.

A typical tablet can have the composition:

	Mg.
(1) Meperidine	100
(2) p-chloroamphetamine ·HCl	10
(3) Starch, U.S.P.	57
(4) Lactose, U.S.P.	73
(5) Talc, U.S.P.	9
(6) Stearic acid	6

55 Powders 1, 2, 3 and 4 are slugged, then granulated, mixed with 5 and 6, then tableted.

A gelatin capsule can contain the following active drugs:

	Mg.
60 Anileridine	50
p-chloroamphetamine ·H ₂ SO ₄	25

The amount of the analgesic, and thus of a substituted amphetamine compound or its non-toxic acid addition salt, will be governed by the activity of the particular analgesic used since the activity varies from one analgesic to another. The following are typical ranges of dosages which can be used in the combinations:

	Mg.
70 A:	50-300
Meperidine	50-300
p-chloroamphetamine ·H ₃ PO ₄	50-350

B:	Methadone	Mg. 2-40
	p-chloroamphetamine fumarate	50-350
C:	Anileridine	25-100
	p-chloroamphetamine maleate	50-350
D:	Alphaprodine	50-200
	p-chloroamphetamine cyclohexanesulfamate	75-350
E:	Piminodine	25-200
	p-chloroamphetamine citrate	75-350
F:	Phenampromide	50-250
	p-chloroamphetamine · HCl	50-350
G:	Diamppromide	10-50
	p-chloroamphetamine sulfate	50-350
H:	Pentazocine	10-200
	p-chloro-N-methylamphetamine	50-350

Such combinations can be formulated into unit dosage forms with or without carriers. They are particularly useful in tablet form. In each of these formulations, or others that will be obvious to one skilled in the art, p-chloroamphetamine or p-chloro-N-methylamphetamine can be replaced with another substituted amphetamine such as m-trifluoromethylamphetamine, m-trifluoromethyl-N-methylamphetamine, p-trifluoromethyl-N-ethylamphetamine, p-nitroamphetamine and p-nitro-N-methylamphetamine in the form of an acid-addition salt.

Although the drugs might be administered by other routes, the oral route is most suitable. The number of unit dosages administered daily is to be prescribed by a physician in light of the patient's general condition and the results to be sought.

Although the subject invention has primary value to humans, it can also be used in lower animals such as dogs and horses and captive wild animals such as in zoos, and particularly in large mammals.

Various changes and modifications of the invention can be made and, to the extent that such variations incorporate the spirit of this invention, they are intended to be included within the scope of the appended claims.

What is claimed is:

1. The method of inducing an analgetic effect in an animal which comprises simultaneously or concomitantly administering to the animal about 2 to 300 mg. of a synthetic analgetic selected from the group consisting of meperidine, methadone, anileridine, alphaprodine, piminodine, phenampromide, codeine, or pentazocine and about 10 to 350 mg. of a substituted amphetamine compound of the formula

wherein R is hydrogen or lower alkyl and R₁ is halo, nitro or trifluoromethyl, or a nontoxic acid addition salt thereof.

2. The method of claim 1 in which the substituted amphetamine compound is p-chloroamphetamine, p-chloro-N-methylamphetamine, m-trifluoromethyl-

amphetamine, m-trifluoromethylamphetamine, p-trifluoromethyl-N-ethylamphetamine, p-nitroamphetamine or p-nitro-N-methylamphetamine.

3. A pharmaceutical composition in unit dosage form containing about 2 to 300 mg. of a synthetic analgetic of the group consisting of meperidine, methadone, anileridine, alphaprodine, piminodine, phenampromide, codeine, or pentazocine and about 10 to 350 mg. of a substituted amphetamine compound of the formula

wherein R is hydrogen or lower alkyl and R₁ is halo, nitro or trifluoromethyl, or a nontoxic acid addition salt thereof.

4. A pharmaceutical composition according to claim 3 in which the substituted amphetamine compound is p-chloroamphetamine, p-chloro-N-methylamphetamine, m-trifluoromethylamphetamine, m-trifluoromethyl-N-ethylamphetamine, p-trifluoromethyl-N-ethylamphetamine, p-nitroamphetamine and p-nitro-N-methylamphetamine.

5. A pharmaceutical composition according to claim 4 containing about 50 to 300 mg. of meperidine and about 50 to 350 mg. of p-chloroamphetamine.

6. A pharmaceutical composition according to claim 4 containing about 20 to 40 mg. of methadone and about 50 to 350 mg. of p-chloroamphetamine.

7. A pharmaceutical composition according to claim 4 containing about 25 to 100 mg. of anileridine and about 50 to 350 mg. of p-chloroamphetamine.

8. A pharmaceutical composition according to claim 4 containing about 50 to 200 mg. of alphaprodine and about 50 to 350 mg. of p-chloroamphetamine.

9. A pharmaceutical composition according to claim 4 containing about 25 to 200 mg. of piminodine and about 50 to 350 mg. of p-chloroamphetamine.

10. A pharmaceutical composition according to claim 4 containing about 50 to 250 mg. of phenampromide and about 50 to 350 mg. of p-chloroamphetamine.

11. A pharmaceutical composition according to claim 4 containing about 10 to 50 mg. of diamppromide and about 50 to 350 mg. of p-chloroamphetamine.

12. A pharmaceutical composition according to claim 4 containing about 10 to 200 mg. of pentazocine and about 50 to 350 mg. of p-chloro-N-methylamphetamine.
